US00D595149S

(12) **United States Design Patent**
Friedland et al.

(10) **Patent No.:** **US D595,149 S**
(45) **Date of Patent:** **** Jun. 30, 2009**

(54) **CONCAVE THERMOFORM BASE WITH
FOOD PLACEMENT VACUUM**

(75) Inventors: **Jason Michael Friedland**, Franklin, TN (US); **Angel Eduardo Hernandez**, Nolensville, TN (US); **Rebecca Morgan Valentine**, Franklin, TN (US); **Peter Sebastian Slusarczyk**, Nolensville, TN (US)

(73) Assignee: **MARS, Incorporated**, McLean, VA (US)

(**) Term: **14 Years**

(21) Appl. No.: **29/322,019**

(22) Filed: **Jul. 28, 2008**

Related U.S. Application Data

(62) Division of application No. 29/287,524, filed on Aug. 17, 2007, now Pat. No. Des. 578,013.

(51) **LOC (9) Cl. 09-05**

(52) **U.S. Cl. D9/707**

(58) **Field of Classification Search** D9/703-710, D9/713-714, 430-432, 414, 418, 424; 383/113, 383/114, 45, 47, 200, 203, 100, 108; 229/200, 229/87.06; 426/106

(57) **CLAIM**

The ornamental design for a concave thermoform base with food placement vacuum, as shown and described.

DESCRIPTION

FIG. 1 is a perspective view of a concave thermoform base with food placement vacuum showing our new design;

FIG. 2 is a top view of the design shown in FIG. 1;

FIG. 3 is a bottom view of the design shown in FIG. 1;

FIG. 4 is a front view of the design shown in FIG. 1;

FIG. 5 is a rear view of the design shown in FIG. 1; and,

FIG. 6 is a left side view of the design shown in FIG. 1, wherein the right side view is a mirror image thereof.
